CLAIM

The ornamental design for a corner paint roller, as shown and described.

DESCRIPTION

FIG. 1 is a front view of a corner roller showing my new design;

FIG. 2 is a side view (left end side) of said roller illustrated in FIG. 1;

FIG. 3 is a top view of said roller;

FIG. 4 is a side view (right end side) of said roller;

FIG. 5 is a back view of said roller, similar to the view of

FIG. 1; and,

FIG. 6 is the bottom view of said roller.
